UNITED STATES PATENT OFFICE.

JAMES C. COVERT, OF WATERVLIET, NEW YORK.

SNAP-HOOK.

SPECIFICATION forming part of Letters Patent No. 620,569, dated March 7, 1899.

Application filed January 6, 1898. Serial No. 665,810. (No model.)

To all whom it may concern:

Be it known that I, JAMES C. COVERT, a citizen of the United States, residing at Watervliet, in the county of Albany and State of New York, have invented certain new and useful Improvements in Snap-Hooks; and I do hereby declare the following to be a full, clear, and exact description of the invention, such as will enable others skilled in the art to 10 which it appertains to make and use the same.

This invention relates to an improvement in snap-hooks, and it is embodied in the construction hereinafter described, and defined in the claims.

15 The invention relates more particularly to what are commonly known as "bolt-snaps," wherein a spring-pressed bolt is employed, the bolt working in a barrel or cylinder, its outer end resting normally against the nose 20 of the hook.

In bolt-snaps there are what is known as the "core" type, wherein the barrel or cylinder is cast with a core, and that type which I shall term the "turned-over" type, wherein 25 in the blank is cast in substantially trough shape, the upper portions of the sides being afterward turned over, thereby forming the completed cylindrical barrel. My invention pertains to this latter type of snap. In this 30 class of snap-hooks it has been recognized as a necessity to have an opening in the rear of the barrel for the escape of dirt or other foreign material, which if allowed to remain would soon prevent the bolt from having the 35 requisite backward movement into the barrel to wholly remove the locking end of the bolt from the entrance passage-way of the hook proper.

Heretofore various snap structures of the 40 turned-over form, as distinguished from the cored form, have been formed with discharge-openings or dirt-escape holes at their rear ends. The openings have been made and located, however, in such a manner and in such 45 position that the spiral spring will occasionally work out of the hole and also in such a position that the spring will have an uneven or partial back abutment, the spring tending to partially close the hole or opening, preventing the escape of the dirt. An instance 50 of such a structure is that wherein the rear end corners of the wings of the cylinder are

cut off, leaving a V or curved opening at the top of the rear portion. Also long slots have been left between the wings for the free exposure of the interior of the barrel. Also the upper edge of the end-closing lug or ear has been cut out at one side, forming a back opening at the top. The defects incident to such structures have been wholly overcome by the 60 present invention, which may therefore be said to consist generally in a turned-over snap having at its rear an abutment which forms an even complete rest for the end of the spring and a central opening for the escape of dirt 65 or foreign matter so located that the end of the spring will not under the usual and ordinary conditions escape or obstruct the opening.

In the accompanying drawings I have shown 70 a form of hook embodying this invention for the purpose of illustration only, and I wish it to be understood that the invention is not limited to the construction shown.

In the drawings, Figure 1 is a perspective 75 view of the hook. Fig. 2 is a plan view of a blank. Fig. 3 is a rear end view of a blank. Fig. 4 is a longitudinal section of a hook. Fig. 5 is a cross-section on the line x x, Fig. 4; and Fig. 6 is a rear view of a modified form. 80

In the drawings, A designates the body or barrel portion, which is cast conveniently with its sides or wings a open or trough-shaped.

B designates the hook portion, C the sliding bolt, and D the coiled spring. 85

In forming the barrel the sides a are in a well-known manner bent in toward each other, forming what I term a "turned-over" barrel, which consequently has a longitudinal split and in the chamber of which the bolt and 90 spring are located.

On the inner faces of the extreme rear end portions of the wings a are formed inwardly-extending flanges E. These flanges extend but partially across the interior of the barrel 95 or space between the wings and are united at their lower edges with the continuous cross-flange F, lying along and integral with the base or lower walls of the body within, however, the confines of the wings. The flanges 100 E are cast perpendicular, as shown in Figs. 4 and 5, and taper from their lower ends upward, the inclination, however, being more pronounced on their outer faces, as shown in

Fig. 5, whereby the tops of the flanges are arranged forwardly beyond the plane of the end of the base of the body. The rear ends of the wings slope correspondingly. The upper 5 edges or the flanges are beveled off downward from the outer edge, as shown at *e*, Fig. 3, so that when the wings and flanges are bent inward the inclined edges will come together and a close contact of the outer edges of the 10 wings can be secured, as shown in Fig. 5.

In forming the barrel the wings and flanges are both bent on a curve inward toward each other, as above intimated. The flanges being 15 tapered will bend along the proper points to form the proper arcs, and when so bent the rear of the barrel will be formed with a circular abutment consisting of flanges *E* *F* and through the center will be a substantially circular hole. I have found by experiment that 20 when the rear edges of the wings and the rear faces of the flanges are straight or perpendicular by bending the parts the upper ends will bend out or backward, leaving an overhanging portion, which is ordinarily objectionable.

I believe I am the first to ever successfully produce a turned-over snap with flanges within the confines of the sides for the purposes indicated, and to thereby form a turned-over 30 snap in every respect equal and superior to the cored snap.

I have shown a modified form in Fig. 6, wherein the flanges *H* are shortened and the wings project above the same, the latter being 35 turned over in completing the barrel.

Having thus described the invention, what is claimed as new, and desired to be secured by Letters Patent, is—

1. A bolt snap-hook comprising a hook portion, a barrel portion having one side split or 40 separated longitudinally, a sliding bolt, a spring in the rear of the bolt within the barrel, and an abutment within the rear portion of the barrel having an opening therein of a diameter less than the diameter of the chamber 45 within the barrel and against which the rear end of the spring rests, substantially as described.

2. A bolt snap-hook comprising a hook portion, a barrel portion having one side split or 50 separated longitudinally, a sliding bolt, a spring in the rear of the bolt within the barrel, and an abutment having an inclined face, located within the rear of the barrel and having an opening therein of a diameter less than 55 that of the chamber in the barrel, substantially as described.

3. A bolt snap-hook blank having a substantially trough-shaped body or barrel portion, a hook portion at the forward end of the 60 body portion and an inwardly-extending abutment-flange within the rear portion of the body.

4. A bolt snap-hook blank having a substantially trough-shaped body or barrel portion, a hook at the forward edge of the same and an inwardly-extending abutment-flange within the rear portion of the body, having oppositely-inclined upper edges, substantially 65 as described.

In testimony whereof I affix my signature in presence of two witnesses.

JAMES C. COVERT.
